UNITED STATES PATENT OFFICE.

HARRY H. DANIELS, OF WINTHROP, MASSACHUSETTS.

ATTACHER FOR BUTTON-FASTENERS.

1,394,476.

Specification of Letters Patent.

Patented Oct. 18, 1921.

Application filed December 19, 1919. Serial No. 346,005.

To all whom it may concern:

Be it known that I, HARRY H. DANIELS, a citizen of the United States, and resident of Winthrop, county of Suffolk, Commonwealth of Massachusetts, have invented an Improvement in Attachers for Button-Fasteners, of which the following description, in connection with the accompanying drawings, is a specification, like characters on the drawings representing like parts in each of the several views.

This invention relates to means for attaching and clamping buttons and the like to a material piece or body to which they are to be secured. While having other and more general fields of usefulness the invention is well adapted and designed for securing a fastener button to a flexible sheet such as an automobile curtain or the like, a particular form of such a fastener button being shown and claimed in my co-pending application Serial No. 346,004, filed December 19, 1919. A principal object of the invention is to provide a simple and inexpensive yet highly efficient and reliable means of securing and clamping a button or the like to a curtain or other member. A further object is to provide an attaching device that permits the button to be instantly and most conveniently clamped in assembled relation with the curtain, the improved means provided being of a character to strongly clamp and hold the button in place by a frictional engagement over a substantial area of the curtain and without requiring any penetrating prongs or the like which would be apt to tear or mutilate the curtain. The foregoing and other objects and advantages of the invention will more fully appear from the following detailed description, and the distinctive features of novelty will be pointed out in the appended claims.

Referring to the drawings:

Figure 1 is a plan view of a button base embodying the invention and shown applied to a curtain or the like;

Fig. 2 is a diametrical section on line 2—2 of Fig. 1, the top portion of the body being broken away;

Fig. 3 is a similar diametrical section on line 3—3 of Fig. 1; and

Fig. 4 is an enlarged diametrical section showing an illustrative form of a complete fastener button and socket therefor, with

the button base clamped to the curtain by the improved device of my invention.

10 indicates a ring disk adapted to be applied to the under side of a curtain C, or like material piece. This ring may be 60 equipped with penetrating points 10^a to prevent relative turning thereof with respect to the curtain. The central portion of this ring is formed with a flange collar 11 that is adapted to be passed through a hole 65 therefor in the curtain and to project some little distance from the upper side thereof. 12 indicates the button base which in accordance with my invention consists in a ring 12^a having a series, shown as four, of 70 spring arms 12^a projecting radially inward therefrom and terminating at equal and predetermined distances from the center of the ring, which distance is very slightly greater than the external diameter of the flange collar 11. The inner extremities of these 75 prongs are preferably curved so as to fit as closely as may be the circular section of the collar 11, it being of course understood that this circular section is a merely illustrative and preferred form. The ring 12 may also be provided intermediate the prongs 12^a with turned-down points 12^b adapted to penetrate slightly into the material as the ring 80 is pressed into place, these points being merely to prevent the ring from turning and the use thereof being, like the use of the points 10^a, optional. In other words in cases where it is desired to avoid the use of 85 any penetrating points whatever, the device may be assembled and clamped to the curtain as now to be explained, without such penetrating points. In assembling the device in place the ring 12 is applied to the 90 curtain opposite the ring disk 10 and the collar 11 is forcibly pressed through the opening between the inner ends of the prongs 12^a, springing and bending these 95 prongs slightly outward and upward. The 100 ring 12 and the ring disk 10 are thus pressed from opposite sides of the material to closely and tightly clamp the same and the prongs 12^a pressing closely against the collar 11 will prevent any relative loosening or giving 105 backward of the button base 12. The button borne by the base 12 may be of any preferred character, but as herein shown this consists in a housing 13 in which is fitted a slid able 110 stud 14 having a projecting head 15 and a

flange 16 limiting the outward movement of said head. This housing may be secured to the base 12 in suitable manner, as by having a plurality of prongs 13^a depending therefrom passed through holes therefor in the base and turned inward as indicated in dotted lines in Fig. 4. A compression spring 17 fitted on the stud presses against the flange 16 to normally hold the stud at an outward limit of movement, this spring reacting against a flange collar 18 secured to the disk 10. The inner end of the stud 14 is adapted to be pressed into a self-clamping socket composed of a shallow housing 19 in which is fixed a ring 20 having inwardly projecting radial prongs 20^a which are adapted to engage the stud and lock the same against removal by a binding action similar to that already described with respect to the prongs 12^a. These prongs 20^a may however be pressed out of binding engagement with the stud to release the button at will by engagement of the flange collar 18 therewith, this being accomplished by pressing inward on the body or housing 13 of the button, these features being however more fully described and claimed in my said copending application. I am aware that the invention may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the invention.

Having described my invention, what I claim as new and desire to secure by Letters 40 Patent is:

1. An attacher for a button base, comprising clamping members for engaging opposite sides of a material piece, one thereof having a projection through said material piece, and the other thereof having means permitting said projection to be passed freely therethrough to operative position and adapted for automatic self-binding engagement with said projection as said members are pressed into assembled relation.

2. An attacher for a button base, comprising clamping members for engaging opposite sides of a material piece, one thereof having a projection through said material piece, and the other thereof having a movable part permitting said projection to be passed freely therethrough to operative position and self-engageable for wedging action with said projection as said members are placed into assembled relation, to hold them from disengagement. 55

3. An attacher for a button base or the like, comprising clamping members for engaging opposite sides of a material piece, one thereof having a projection through said piece, and the other thereof having a plurality of inwardly extending prongs arranged to permit said projection to be pressed freely therethrough to its operative position and adapted to engage said projection as it is pressed therethrough for automatic self-clamping action with respect thereto to prevent disengagement of said members. 65

4. An attacher for a button base, comprising clamping rings for engaging opposite sides of a curtain or the like, one thereof having a projection through said curtain, and the other having a plurality of spaced apart spring prongs extending radially inward therefrom, and adapted to have said projection pressed between the extremities thereof to spring said prongs outward and exert a self-binding clamping action with respect to said projection to hold said members interengaged. 75

5. An attacher for a button base or the like, comprising clamping rings for engaging opposite sides of a curtain or the like, one thereof having a flange collar projecting through the curtain, and the other thereof having radially extending spring prongs adapted to receive said collar between them and be pressed outward thereby so as to exert a self-binding clamp thereon, and a button housing mounted on the last named member. 90

In testimony whereof, I have signed my name to this specification.

HARRY H. DANIELS.
